UNITED STATES PATENT OFFICE.

OLE STOLTEMBERG, OF TACOMA, WASHINGTON.

BED DAVENPORT.

Application filed July 25, 1927. Serial No. 208,200.

This invention relates to davenports and especially to that class thereof which are adapted to be extended to form a bed.

The objects of the invention are, first, to provide such a bed davenport which is as strong in its framing as the usual davenport; second, to provide such a davenport which is, in no way, distinguishable in appearance from the usual davenport; third, to provide means whereby the spring parts of the davenport bed lie in the same plane with and are alternated with the corresponding parts of the fixed portion of the davenport; fourth, to provide means for bridging the space between the spring portions of the bed extension; fifth, to provide means for bridging the space between the spring parts of the fixed portion of the davenport, when the bed part thereof is extended; sixth, to provide improved guiding means between the fixed part and the extension whereby the motion of the extension is controlled and whereby it is prevented from binding, even if it is pulled or pushed from one of its corners; and seventh, to provide means adapted to hold the bed portion in extended position until it is desired to return it to its normal or closed position. A further object is to provide a means for mounting the springs of the davenport and its extension, whereby they form integral groups or cushions. Another object is to provide automatic legs for the bed extension whereby, when the bed is in extended position, the legs automatically assume a supporting position and whereby, when the bed is being returned to its closed position, the said legs are withdrawn and stowed away automatically. A further object is to provide a bed davenport which is simple and economical to manufacture, easy to operate, and which provides ample spring support either as a spring mattress for the bed or as a spring seat for the davenport.

I attain these and other objects by the devices, mechanisms, and arrangements illustrated in the accompanying drawings, in which—

Fig. 1 is a front elevation of the bed davenport, in its closed position; Fig. 2 is a side elevation of a portion of the end of the extension frame and the supporting fixed frame, in extended position, to illustrate the automatic latch between the parts; Fig. 3 is a cross-section of the rear canvas apron roll, showing it in partly extended position and in relation to two adjacent spring cushions; Fig.

4 is a perspective view of the central portion of the davenport, showing the bed portion partly extended and illustrating the means for guiding the extension frame on the fixed frame; Fig. 5 is a perspective view of the bed davenport in extended position, with all the upholstery removed and showing a portion of the rear canvas apron and roller broken away to reveal the arrangement of the spring cushions thereunder; Fig. 6 is a similar view thereof, showing the parts in closed position; Fig. 7 is a side elevation of the automatic leg for the bed portion, in operative position; Fig. 8 is a similar view thereof, showing it in stowed position; Fig. 9 is a perspective view of a part of one of the spring cushions, showing one spring only therein, to illustrate its construction; Figs. 10 and 11 are cross-sections of the bed davenport in closed and extended positions, respectively, the upholstery thereof being shown in outline by broken lines.

Similar numerals of reference refer to similar parts throughout the several views.

The fixed portion of my improved bed davenport is made with a frame which is very similar to the usual construction of a davenport incapable of extension and is in every way as strong thereas. This frame comprises a front lower rail 1, supported on three front legs 2; a parallel rear lower rail 3, supported on two legs 4, which extend upward to form the ends 5 of the back framing, indicated by the parts 6 extending between the said end posts 5; together with two side or end frames, formed of the lower horizontal rails 7, joining the above described front rail 1 with the rear rail 3, the front arm posts 8 and the arm frame rails 9, joining the posts 5 and 8. Besides the above, there is a central rail 10, positioned at a lower level than the rails 1 and 3, to which it is secured, and forming a guide for the bed extension, as hereinafter described. The fixed frame is also provided with means for supporting the fixed portion of the spring seat and bed. The lower rear rail 3 of the fixed frame is best illustrated in Figs. 4, 10 and 11, that form shown in Figs. 5 and 6 being a variation thereof. The lower rail 3 is preferably provided with a rabbet 11 extending from end to end thereof and positioned on a level with the upper side of the front rail 1. A series of parallel spring cushion-supporting slats 12 are secured in said rabbet 11 and extend therefrom to the

front rail 1, on which they rest and to which they are suitably secured. These slats 12 are spaced apart a sufficient distance to permit a similar series of slats on the bed extension 5 to lie between them as hereinafter described.

The bed or extension frame comprises a rear rail 13, positioned on the same level as the above-described front rail 1 of the fixed frame, and lying above the above-described 10 central rail 10; with two end rails 14 and a front rail 15. The level of the front rail 15 is above the upper surface of the front fixed rail 1, as clearly seen in Figs. 8 and 10. The extension frame is also provided with a central rail 16, extending from the rear rail 13 15 to the front rail 15, and lying immediately above the level of the fixed front rail 1 (Fig. 4). This extension frame is also provided with a series of parallel spring cushion-supporting slats 17, secured to the front and rear rails 15 and 13 thereof, and lying between the slats 12 of the fixed frame, as above described.

The extension frame is supported, at its 25 rear, by the fixed frame, especially at the ends and center by the rails 7 and 10, and at its front, by means of two retractable legs, illustrated in Figs. 7 and 8. These legs comprise suitably shaped leg bodies 18, pivoted at 19 to 30 the end rails 14 of the bed extension, near the front thereof, and each having their upper surfaces curved substantially as shown in the drawings, and a helical spring 20, one end of which is secured to the upper part of the leg, 35 above the pivot 19 and the other end of which is secured to the said rail 14, said spring being always under tension. Thus, when there is nothing to hold the lower end of the leg 18 up, the spring 20 turns it on its pivot 19 and 40 brings its lower end down into contact with the floor. A stop 21 is provided in such position as to limit the motion of said leg to such vertical position. When, however, the extension frame is moved rearward to close it, 45 the leg 18 first slides along the floor and then engages the front rail 1 of the fixed frame, at a point below the pivot 19, and is thus turned thereby on its pivot into its retracted position, as shown in Fig. 8, against the action of the 50 spring 20. The leg 18 remains in this position, resting on top of the front rail 1, until the extension frame is drawn out again, when it again turns vertical as soon as it is removed from contact with the said front rail 1 55 of the fixed frame.

I prefer to place metal gliders 22 between the several moving parts in order to cause a free and smooth motion therebetween, with but little friction. In Fig. 2 I have shown a 60 glider 22 mounted on the upper side of the fixed supporting end rail 7, at the front end thereof, and a similar glider 22, in reversed position, on the lower side of the rear end of the end rail 14 of the extension frame. Also, in said view, it will be seen that I have pro-

vided notches 23 in the said several parts 7 and 14, adapted to receive the gliders 22 of the other part when the extension frame is at its extended position, said notches 23 being quite shallow in depth and with an easy incline. 70 These notches, cooperating with the said gliders 22, tend to hold or latch the extension frame in its extended position. However, when it is desired to close the frame from its extended position, it is only necessary to raise 75 slightly thereon or, indeed, to push inward thereon with sufficient force to cause the said gliders to slide up out of the said notches 23, and the extension frame will then slide easily and smoothly back into its closed position. 80

Referring now particularly to Fig. 4 of the drawings, wherein the means for guiding the movement of the extension frame on the fixed frame is illustrated, it will be seen that the central guide rail 16 of the extension frame 85 lies immediately over the corresponding guide rail 10 of the fixed frame. The front rail 1, of the fixed frame, is provided with two guiding flanges 24 which extend upward therefrom and which engage the two sides of 90 the said extension guide rail 16. Also the rear rail 13 and the rear end of the said guide rail 16, of the extension frame, are provided with guiding lugs or flanges 25, which extend downward therefrom and which engage 95 the two sides of the said fixed guide rail 10. Thus it will be seen that the extension frame is guided at its center by the interaction of the guiding lugs 24 and 25 on the respective 100 guiding rails 16 and 10, and that they prevent any jamming of the extension frame in relation to the fixed frame as they engage the respective parts at well separated positions.

Referring now to Fig. 9 of the drawings, in which I have particularly illustrated the construction of one of the spring cushions which form an important part of my invention. This spring cushion consists of a rectangular casing of fabric in which the series of springs for the seat or bed are mounted, and which forms a long spring body, flexible in all directions, which groups the set of springs therein into an aligned spring cushion, which is self-contained and which is of reasonable stiffness longitudinally thereof. Each cushion, then, comprises one of the above described slats 12 on which are fastened a row or series of helical springs 26, and to which the fabric container 27 is secured. This cushion, then, consists of a fabric box, extending substantially the length of the slat on which it is formed, and enclosing a group of springs 26, said springs being under an initial compression, and being secured to the said fabric box at convenient points therein. In practice I prefer to form the springs 26 with rectangular upper and lower coils or loops, as shown in Fig. 9, so that two adjacent springs will have their upper and lower coils close together and they may be fastened to the supporting slat 125 130

12, or to the fabric 27 at the same place, and so that the said rectangular upper coils will shape the fabric box 27 with substantially straight upper edges. Thus it will be seen 5 that each slat 12 is provided with a spring cushion of rectangular form, whose sides are in tension under the action of the springs contained therein.

It will be seen by the drawings, as Figs. 5 10 and 6, that there are two sets of these spring cushions, the cushions 28 being mounted on the slats 12 of the fixed frame, and the similar cushions 29 which are mounted on the slats 17 of the extension frame and that, 15 when the davenport is closed (Figs. 1, 6 and 10), these two series of cushions 28 and 29 alternate in position to form the spring seat thereof and, when it is extended, each set of 20 spring cushions 28 and 29 form a portion of the bed thus formed.

The fabric spring cushions 29, which are mounted on the slats 17 of the bed extension frame, are elevated very slightly above the spring cushions 28 on the slats 12, of the fixed 25 frame, as clearly shown in Figs. 3, 5, 6, 10 and 11. All the said spring cushions 29 of the extension frame are secured together by means of two, or more, flexible connections such as wires 30, which are secured thereto 30 and which stretch across and bridge the tops of all the said series of spring cushions 29, and which are secured to the end rails 14 of the extension frame through the interposition of coiled springs 31. Thus, although 35 each said spring cushion 29 is fairly rigid or stiff longitudinally, on account of the fact that the springs are alined in that direction, they are stiffened transversely of the said slats by being connected together by the said 40 wires 30. Since the said spring cushions 29 are higher than those on the fixed frame, it is evident that the said bracing wires 30 pass over the tops of the said other spring cushions 28 on the fixed frame. However, the said 45 lower spring cushions 28, on the fixed frame, are also attached together along their rear upper edges by means of the wire 32 (Figs. 3, 5, 10 and 11) which is stretched between the ends of the fixed frame, and which has 50 a spring connection thereto, not shown.

When the davenport is closed, therefore, the spring cushions 29, of the extension frame, are alternated with the spring cushions 28, of the fixed frame. The two sets of spring 55 cushions are not in any way attached together but each set is secured together into a single resilient structure, as above described. The one resilient structure is interpositioned in the other resilient structure. Thus the 60 whole seat formed by the alternating spring cushions 28 and 29 forms a stiff spring body of great resiliency.

A roller 33 is mounted in the rear framing of the fixed portion of the davenport, at a 65 point below the spring cushions forming the

back thereof, said roller having an internal torsion spring 34 (Fig. 3) mounted therein and tending to resist its rotation in an unwinding direction, as hereinafter outlined. An apron 35 is rolled on the said roller 33 and 70 is attached thereto at its inner end and to the rear upper edges of all the spring cushions 29, of the extension frame, at its outer end. This apron is made of heavy fabric, such as canvas. Wires 36 are secured to said canvas 75 apron 35, one such wire being positioned at the outer edge thereof and to the several spring cushions 29, the other wires 36 being parallel therewith and spaced at short intervals apart, all said wires being parallel to the 80 axis of said roller 33 and at right-angles to the axes of the several spring cushions forming the davenport. When the extension frame is drawn outward, the spring cushions 29 pull the canvas apron 35 and unwind it 85 from the roller 33, against the action of the spring 34 therein, and said canvas apron slides over the fixed spring cushions 28, as the extension moves outward, said apron and its wires 36 bridging across said fixed cushions 90 and therefore reenforcing them laterally and distributing the weight applied thereto among the several cushions 28. The spring 34 always tends to draw said extension frame inward and it is held outward by the above 95 described latch formed by the gliders 22 and the notches 23. When the extension frame is returned into its closed position, by being pushed inward manually and by the action of said spring 34, the said apron 35 is removed 100 from over the cushions 28 and is rolled on the roller 33, under the action of said spring 34.

Having, therefore, described my invention, what I claim is:—

1. A bed davenport comprising a fixed 105 frame; spring cushions mounted on said fixed frame in spaced relation to each other; an extension frame, supported and guided by said fixed frame; spring cushions, similar to said first spring cushions, mounted on said extension frame in spaced relation to each other and positioned to alternate with the said first spring cushions, said second spring cushions being higher than the first spring cushions; a wire securing all said second 110 spring cushions together and to said extension frame and lying above the level of said first spring cushions; a roller mounted on the rear of said fixed frame; and a fabric apron mounted on said roller and secured at its 115 outer end to the inner ends of said second spring cushions and adapted to lie on said first spring cushions.

2. A bed davenport comprising a fixed 125 frame; spring cushions mounted on said fixed frame in spaced relation to each other; an extension frame, supported and guided by said fixed frame; spring cushions, similar to said first spring cushions, mounted on said extension frame in spaced relation to each 130

other and positioned to alternate with the said first spring cushions; means securing all said second spring cushions together and to said extension frame, and lying above the 5 level of said first spring cushions; and a fabric apron secured to the inner ends of said second spring cushions and adapted to lie on said first spring cushions; together with means for drawing said fabric apron from 10 over said first spring cushions when said extension frame is in its closed position.

3. A bed davenport comprising a fixed frame; spring cushions mounted on said fixed frame in spaced relation to each other; an 15 extension frame, supported and guided by said fixed frame; spring cushions, similar to said first spring cushions, mounted on said extension frame in spaced relation to each other and positioned to alternate with the 20 first spring cushions, said second spring cushions being higher than the first spring cushions; means securing the tops of all said second spring cushions together and bridging the space therebetween, and lying above 25 the level of said first spring cushions; and means lying over said first spring cushions and bridging the space therebetween when said extension frame is in extended position.

4. A bed davenport comprising a fixed 30 frame; spring cushions mounted on said fixed frame in spaced relation to each other; an extension frame, supported and guided by said fixed frame; spring cushions, similar to said first spring cushions, mounted on said 35 extension frame in spaced relation to each other and positioned to alternate with the first spring cushions, said second spring cushions being higher than the first spring cushions; and means securing the tops of all said second spring cushions together and to said extension frame, and bridging the space therebetween, and lying above the level of said 40 first spring cushions and adapted to slide thereover when the extension frame is in 45 closed position.

5. A bed davenport comprising a fixed frame; spring cushions mounted on said fixed frame in spaced relation to each other; an extension frame, supported and guided by 50 said fixed frame; spring cushions, similar to said first spring cushions, mounted on said extension frame in spaced relation to each other and positioned to alternate with the first spring cushions; means securing the rear edges of the tops of all said first spring 55 cushions together and to said fixed frame; and means, secured to said extension frame, and lying over said first spring cushions, and bridging the space therebetween when said extension frame is in extended position. 60

6. In a bed davenport, a fixed frame having horizontal end rails; an extension frame mounted on said end rails and adapted to be slid thereon into extended position; an upward extending metal glider secured to the front end of the end rail of said fixed frame, and engaging the under side of the extension frame to reduce the friction thereof on the fixed frame; a downward extending metal glider secured to the extension frame 70 and engaging the upper side of the end rail of said fixed frame, to reduce the friction of said extension frame on the fixed frame; a pair of complementary notches, one in the 75 under side of said extension frame and adapted to engage the glider on the end rail, and the other in the upper side of said end rail and adapted to engage the glider on said extension frame, said gliders and notches being positioned to simultaneously engage each other, whereby the extension frame is latched in its extended position; a spring actuated roller mounted in said fixed frame; and means connecting said roller to said extension frame, whereby said extension frame is 80 pulled towards its closed position when said gliders are out of engagement with said notches. 85
